UNITED STATES PATENT OFFICE.

DAN MARTINI, OF LONDON, ENGLAND.

APPARATUS FOR IONIZING PETROLEUM AND ITS DISTILLATES.

No. 908,297.

Specification of Letters Patent.

Patented Dec. 29, 1908.

Application filed May 29, 1908. Serial No. 435,670.

To all whom it may concern:

Be it known that I, DAN MARTINI, a citizen of the United States of America, residing at London, England, have invented a certain new and useful Improved Apparatus for Ionizing Petroleum and its Distillates, of which the following is a specification.

My invention consists of an apparatus for effecting an electronic interchange between the ions in crude petroleum or any distillate of petroleum and the ions in atmospheric oxygen, which interchange not only shatters the molecular structure of the hydrocarbons but forms the constituents into new radioactive groups and produces a mixture with high explosive efficiency, and very suitable as an explosive mixture for use in internal combustion engines.

The principle underlying my invention is the discovery that petroleum, in its crude and denser forms, contains properties which have not hitherto been correctly defined or put to commercial use. These properties are as follows:—Crude petroleum contains a substance which behaves like radium and gives the gases obtained from petroleum a high electric conductivity. Electrons, both free and bound, reside to a large extent in the hydrocarbons forming these gases. Petroleum, either crude or in its fractions, is exceedingly susceptible to ionic charge, *e. g.* by means of ionized oxygen or ionized air. The hydrocarbons contained in crude petroleum when subjected to ionic charge in a gaseous state in the presence of ionized oxygen, do not on ignition, first decompose into hydrogen and carbon in primary and secondary reactions but they explode simultaneously when fired by an electric spark. Now according to my said invention, I utilize these properties in the production of a highly efficient explosive mixture for use in internal combustion engines. For this purpose, I ionize oxygen or atmospheric air and mix this ionized oxygen or air with petroleum or any distillate thereof in the form of a mist or spray and I ionize this mixture by means of a suitable ionizer wherein the said mixture is simultaneously subjected to expansion or preferably to a series of expansions. By this means, an explosive mixture is obtained which is capable of exploding in one chemical reaction, so that a very complete combustion of the petroleum or of its distillate is obtained.

My said invention moreover comprises an apparatus, to be hereinafter described, whereby my improved process may be carried into practice.

In the accompanying drawings, Figure 1 is a vertical central section of the complete apparatus for carrying out my invention, and Fig. 2 is a view showing a detail of construction.

The sparking chamber is constituted by a short length of tube *a* of glass or other insulating material and which may be of square cross-section. The width of said chamber is sufficient to permit insertion therein of the electrode plates *b*, *b*, which are provided with points on their opposing surfaces and are held at suitable distances apart, *e. g.* an eighth to a quarter of an inch, by means of grooved or toothed separators *c*, *d* of porcelain, ebonite or other suitable insulating material arranged in metal frames *e*, *f*. If desired, hollow, preferably cylindrical electrodes can be employed which are arranged coaxially one within the other. When more surface with points is required in a small space, in cases where two coaxial electrodes are employed, the inner electrode as seen endwise is star-shaped and the slopes of such protruding surfaces are covered with points. The larger electrode must then have internal corrugations corresponding thereto. If the electrodes are made or cast with the said points in longitudinal rows, they should be adjusted so that each row of points on one electrode projects between rows on the opposite electrode. The points must not touch, and on the electrodes being placed in position, the air space between them should be the same all round. In cases where the electrodes are of circular cross-section, the tube *a* is made of corresponding form.

The frames *e*, *f* are provided with apertures of suitable size to permit the passage through them of the air or oxygen to be ionized. The lower frame *e* is provided with a cylindrical extension *g* which fits into a socket *h* at the upper or inlet end of a spherical mixing chamber *j* and the upper frame *f* is provided with a central eye *k* through which extends a hollow bolt or tube *l* secured in a transverse bracket *m* in the mixing chamber *j*. A nut *n* on the upper screw-threaded end of the tube *l* holds the whole apparatus together. The tube *l* is provided inside the sparking chamber with an external sleeve *o* of suitable insu-

lating material and the central electrodes are cut away in the middle to provide room for said tube. The electrodes *b*, *b* may be made of copper or other suitable material for example aluminium which is very suitable on account of its cheapness, conductivity and high ionizing capacity; the sparking points are shown cast with the electrodes. Alternate electrodes are connected together in any suitable manner the conductors leading from said electrodes to the respective poles of the electric generator extending through the apertures in the insulator *d* and frame *f*.

Some frictional ionization of the air is obtainable, prior to subjecting it to electric action, by extending the sparking chamber at the air-inlet end and by filling the hollow space so formed with loose copper scraps or turnings which are kept in place *e. g.* by a strainer made of copper mesh. Atmospheric air, drawn by the suction of the engine through a glass tube filled with copper in this way, has imparted to it an ionization which increases its electrical conductivity three or four times.

The lower end of the mixing chamber *j* opens through a tubular passage *p* into the second or cone chamber and this communication is fitted underneath with a strong valve *q* controlled by a spiral spring *r*. Spirally disposed within said sphere and integral therewith are narrow flanges *s* winding from the upper to the lower end to give a rotary motion to the mixture passing through the chamber. The spherical chamber *j* is preferably made of aluminium and may be cast integrally with the outer casing *t*, which contains conical electrodes *u*, *v*, or it is cast or made in one piece by itself and screwed to said outer casing as shown in the drawings.

The conical electrodes *u*, *v* in the second or cone-chamber are made of aluminium or other suitable metal, and are provided with a number of points on their opposing surfaces in a similar manner to the electrode-plates *b*, *b*. In some cases, the said cones may be plain, but they are preferably stepped, for example, as shown. In the latter case, when placed one within the other coaxially, the air entering at the apex and passing through between them receives successively and suddenly *e. g.* a twofold, fourfold, and eightfold expansion before emerging at the base. In the case of plain cones, the expansion is gradual.

The outer cone-electrode *u* at its upper end extends into and bears against a ring *w* of insulating material, which fits into the upper part of the casing *t* and also serves as a bulkhead to prevent the gas from flowing from the mixing chamber *j* through the space between the casing *t* and the outer cone *u* instead of through the annular space or passage between the cones *u*, *v*. If desired the

space between the casing *t* and cone *u* may be also closed at its lower end and a portion of the exhaust gases from the explosion engine passed through it, so as to raise the temperature of the electrodes. The lower end of the cone *u* is supported through insulators *x*, *x* on three brackets *y*, *y*, which are pivotally mounted on the lower surface of the casing *t*, so that they can be swung to one side when it is desired to remove the cone *u*. The current is transmitted to this outer cone by means of a conductor *z* extending through a porcelain or other insulator *2* suitably mounted in the casing *t* and connected to an external terminal *3*.

The cone *v* is mounted within the cone *u* by means of an insulating sleeve *4* on a tubular pillar *5* through which extends the insulated conductor *6* whereby current is transmitted to the said cone, sufficient air-space being left as dielectric between the opposing points of the two electrodes to prevent sparking at high voltages. The position of the cone *v* relatively to the cone *u* can be adjusted by providing the lower end of the pillar *5* with screw-threads extending through a screw-threaded socket *7* in the lower part of the saucer-shaped base *t'* of the casing *t*. The pillar *5* is provided with an external handle *8* whereby it may be readily turned, and with a lock-nut *9* for clamping it in any position to which it has been adjusted, so as to enable the apparatus to work with high or low potential electrical current. Other suitable adjusting means may however be provided for this purpose. The base *t'* of the casing *t* is provided with an outlet *10* for the ionized explosive mixture, whereby said mixture is conducted to the engine. The sparking chamber, if the fitting thereof to the engine so requires, can be fixed at any angle between the vertical and a right angle in relation to the cone chamber.

The hollow rod or tube *l* in the sparking chamber, contains, centrally disposed therein and having an air space around it, an oil supply pipe *11* connected at its upper end with the petroleum storage tank (not shown), suitable means, such as a cock or valve being provided for regulating the flow of oil through said pipe. Such oil supply pipe is flared or tapered internally at its lower end where it is provided with a cone *12* suitably secured therein, so as to leave a narrow annular space for the purpose of spreading the oil flowing down the pipe *11* into a conical sheet and of thus facilitating its atomization. The passage through the pipe *11* can be shut off by means of a small cup or bulb *18* which contains mercury and is secured to a rod or wire *19* extending up through a hole in the cone *12* and through the bore of the pipe *11*, whence it passes out through a stuffing-box or in any other suit-

able manner so as to enable the said bulb to be raised or lowered and thus open and close the lower end of the tube 11. By this means, when the engine is not at work, the flow of oil through the pipe 11 can be effectually shut off by the mercury and at the same time the motion of the rod or wire 19 in the bore of said pipe serves to displace any obstruction that may form therein and thus reduces the risk of interruption of the oil-feed to a minimum. The hollow rod or tube 1, therefore, serves the double purpose of a bolt and an air shaft to convey ionized air from the sparking chamber to the ionizer or sprayer. Said tube is provided at the base of the sparking chamber with slots 13, 13 into which a portion of the ionized air from the sparking chamber is diverted by means of a funnel-shaped deflector 14 arranged around the same. This diverted current of ionized air moves past the flared lower end 15 of the oil supply-pipe 11 into an enlargement 16 of the lower end of the tube 1, carrying with it the oil. The mixture of oil and air issues from the enlargement 16 through a series of lateral nozzles 17, 17 and meets the main current of ionized air from the sparking chamber, thus producing a petroleum mist of extreme fineness. The elasticity of the air is thus used to feed in the oil, and keeps the proportions of oil and air correct. The mixture of the oil spray and air is perfected by the whirling motion imparted thereto by the spiral flange or flanges 8 in the chamber 1, which promotes its uniform distribution around the annular space between the cones *u*, *v*, where it is acted upon by a silent electric discharge and is simultaneously subjected to a series of sudden expansions. If desired, the flow of oil from the flared nozzle 15 may be governed by a feed-pin or needle-valve extending upwards through the bottom of the enlargement 16 and mounted on the spring controlled valve *q*, which pin when drawn down by the suction stroke of the engine admits a supply of oil to the enlargement 16.

The sparking chamber, in the apparatus so constructed, has for its object the ionization of the oxygen in the air drawn therethrough by the suction stroke of the engine. The source of electricity may be an alternating current generator supplying current at about 4,000 volts and upwards. The frequency of the alternating current employed should be at least high enough to enable waves of one to three meters long to be produced. The effect of the electric stresses set up by this current, which is preferably a sparking discharge, is to cause electrons to be set free and go from one point to another. Ionization occurs on the electrons being shot into the molecules of the oxygen of the air passing through the ionizer and throwing

these molecules into disorder. Above 5,500 65 volts the majority of the ions in the oxygen are negatively charged and acquire sufficient velocity to generate other ions by collision.

The second casing or cone chamber is designed to enable the oxygen ions to capture the petroleum spray or fog in the right proportion. What is chiefly required at this stage is to get the exact degree of expansion in the mixture that will induce the particles of oil not only to condense upon 70 the ions, but will also maintain each tiny sphere in the mist in stable equilibrium. The host of ions initially supersaturated with oil on entering this chamber, requires only a slight expansion to form the mixture 75 into a cloud. It is precisely at this point that the great difficulty in petroleum as a fuel is met with, and has to be overcome. The process here is not merely an expansion of the mixture. It is an expansion of the 80 ions, involving a chemical transformation, *i. e.*, to break the complex ring and chain molecules in the heavy hydrocarbons into simpler structures lower down in the same series without cracking the component 85 molecules.

After the primary collision of ions and petroleum in the sphere and the mixture reaches the entrance to the cone chamber, an expansion of 1.25 times the volume is 95 necessary to induce further condensation of the oil on the negative ions. Similar condensation on the positive ions takes place when the expansion is between 1.31 and 1.38 times greater than the initial volume. The 100 mixture then has an appearance like fog.

When the mixture reaches the eightfold expansion, near the base of the cone chamber, it has the required cloudlike formation and is little affected by the leakage from the 105 points. Each corpuscle has all the charge it is able to carry.

An explosive mixture prepared in the manner herein described from the cleanest Pennsylvania crude petroleum has an electric conductivity over eight hundred times greater than normal air. A very poor sample so prepared from the same field has a conductivity which exceeds that of air 114 times. Russian and Roumanian crude petroleum similarly treated have from 70 to 600 times higher conductivity than air. The average of all crude oils will be found in practice to exceed air over 400 times. To arrive at a fairly correct measurement, 120 3.4×10^{-10} electrostatic units may be taken as the charge on the ion.

It is wholly due to the presence of the radioactive substance or emanation in petroleum referred to at the beginning of 125 the specification, and the bringing of its energies into operation, in conjunction with the ionized oxygenated molecules, as de-

scribed, that the crude oil and its heavier distillates can be effectively used as a fuel in internal combustion engines. The extreme conductivity of this radioactive element, or substance, carries the electric spark instantaneously throughout the mixture in the cylinder, with the result that the whole ionized oxygenated hydrocarbon body explodes completely and simultaneously in one chemical reaction, and not successively in primary and secondary reactions.

The number of ions produced is dependent upon the intensity of the electric discharge and can be determined by the conductivity of the gas after being subjected to said discharge. The best petrol, that is hexane C_6H_{14} , gives, when intensity of discharge and ionization are plotted, a curve which is almost a straight line. With an equal amount of ionized oxygen the ionization of the gaseous mixture gradually decreases as the molecular weights increase, so that to compensate for this the amount of ionized oxygen should be increased to correspond with the molecular ratios.

Two nonanes, α and β , are the primary constituents of kerosene oil which is composed almost wholly of "paraffins," C_nH_{2n+2} . The Pennsylvania is slightly more ionizable in its crude state than "olefines" C_nH_{2n} and "naphthenes" $C_nH_{2n}6H_s$, which are the chief hydrocarbons in Russian and Roumanian petroleums. The two latter give better results in the cylinder with a little stronger electric charge as hereinafter specified. This is due to the fact that their bound electrons are harder to dislodge. With all petroleums the capacity of the ionizing apparatus is nearly equal to the piston displacement.

When a chemical series is poorer in hydrogen it readily separates carbon as soot and is more difficult to explode. Ionized ozone, obtained from any known tube or plate apparatus, or compressed oxygen, is in such cases supplied as an auxiliary to the sparkling chamber and enriches the mixture. One gram molecule of ozone sets free 29,600 calories, and adds to the heat units and consequently to efficiency. Ozone decomposes in direct ratio to increase of pressure, but in an ionized form it is much more persistent and the loss in the compression chamber is small at seventy or more revolutions of the engine per minute.

As coke and other tarry products, in the fuel as herein described, can only result from imperfect oxidation I have no trouble with them. The apparatus and cylinder remain clean. Carbon, it may be noted, is much more easily ionized in its corpuscle state than normal air. Ionization gives any sulfur in the oil about ninety per cent greater conductivity. Exhaust gases some-

times show a very small loss in nitrogen. For want of a better term, I may say it disappears by chemical induction.

Crude petroleum contains so much grit and dirt that it must first be carefully strained. Any distillate used in the apparatus should also be strained to remove impurities which may have collected in it.

The electric current for producing the electric field in the second or cone chamber is preferably alternating. It must not be less than four thousand volts, if pure Pennsylvania crude is used. Roumanian crude requires a minimum of 5,500 volts; and Russian, Ohio, Texas, California, Borneo and Trinidad oils give better efficiency with voltage from 6,000 upwards. For motor cabs and omnibuses, a small dynamo with suitable transformer gives sufficient current. The magneto, in such vehicles, can be arranged for the purpose by putting an interrupter in the primary coil of the electric transformer used for raising the potential of the current produced by the magneto.

What I claim is:—

1. An apparatus for the production of an explosive mixture for use in internal combustion engines, said apparatus comprising means for forming petroleum liquid into a mist, spray or vapor and simultaneously mixing it with a gas and means for ionizing said mixture and simultaneously subjecting it to expansion.

2. An apparatus for the production of an explosive mixture for use in internal combustion engines, said apparatus comprising means for ionizing gas arranged in combination with means for forming petroleum liquid into a mist, spray or vapor and simultaneously mixing it with said ionized gas and with means for ionizing said mixture and simultaneously subjecting it to expansion.

3. An apparatus for the production of an explosive mixture for use in internal combustion engines, said apparatus comprising a sparking chamber, a tube extending through said sparking chamber and provided with gas-admission apertures in said chamber, deflectors arranged in combination with said gas-admission apertures, an oil-supply-pipe arranged in said tube, and a spraying device arranged at the outlet end of said tube.

4. An apparatus for the production of an explosive mixture for use in internal combustion engines, said apparatus comprising a sparking chamber, a tube extending through said sparking chamber and provided with gas-admission apertures in said chamber, deflectors arranged in combination with said gas admission apertures, an oil-supply-pipe arranged in said tube, a spraying device consisting of a laterally perforated enlargement of the outlet end of said tube, and

a spherical mixing chamber inclosing said spraying device and provided with a spiral rib on its inner surface.

5. An apparatus for the production of an explosive mixture for use in explosion engines, said apparatus comprising means for forming a petroleum liquid into a mist, spray or vapor, and for mixing the so-treated liquid with a gas, an ionizer comprising two 10 cones arranged one within the other, and a conduit connecting said atomizing or spraying and mixing apparatus to the smaller end of the annular space between said cones.

6. An apparatus for the production of an explosive mixture for use in explosion engines, said apparatus comprising means for forming a petroleum liquid into a mist, spray or vapor, and for mixing the so-treated liquid with a gas, an ionizer comprising two 15 cones having steps on their opposing surfaces and arranged one within the other, and a conduit connecting said atomizing or spraying and mixing apparatus to the smaller end of the annular space between 20 said cones.

7. An apparatus for the production of an explosive mixture for use in explosion engines, said apparatus comprising a sparking chamber, a tube extending through said 30 sparking chamber and provided with gas-admission apertures in said chamber, deflectors arranged in combination with said gas-admission apertures, an oil-supply pipe arranged in said tube, a spraying device consisting of a laterally perforated enlargement 35 of the outlet end of said tube, a spherical mixing chamber inclosing said spraying device and provided with a spiral rib on its inner surface, an ionizer comprising two cones arranged one within the other, and a 40 conduit connecting said mixing chamber to the smaller end of the annular space between said cones.

In testimony whereof I have hereunto set my hand in presence of two subscribing witnesses.

DAN MARTINI.
